UNITED STATES PATENT OFFICE.

HENRY F. ZARTH, OF SHAKOPEE, MINNESOTA, ASSIGNOR TO AMERICAN RANGE CORPORATION, OF SHAKOPEE, MINNESOTA.

DESIGN FOR A RANGE.

Application filed February 11, 1927. Serial No. 20,715. Term of patent 7 years.

To all whom it may concern:

Be it known that I, HENRY F. ZARTH, a citizen of the United States, residing at Shakopee, in the county of Scott, and State of Minnesota, have invented a new, original, and ornamental Design for a Range, of which the following is a specification, reference being had to the accompanying drawing, forming part thereof.

The drawing shows a perspective view of the article, showing my new design; the shape and base of the legs constitutes an important feature of the stove, the base con-

stituting relatively narrow panels having relatively large plain surface portions and convex and then concave and then convex surfaces adjacent their upper edges. The legs are curved inwardly and then outwardly from the base diminishing in cross section from their upper portion to their lower extremities and having sharp corners.

What I claim is:—

The ornamental design for a range, as shown and described.

HENRY F. ZARTH.
